UNITED STATES PATENT OFFICE.

HENRY B. GERMESHAUSEN, OF WOODLAND, CALIFORNIA.

SCRAPER.

1,296,789.

Specification of Letters Patent. Patented Mar. 11, 1919.

Application filed October 14, 1918. Serial No. 257,960.

To all whom it may concern:

Be it known that I, HENRY B. GERMESHAUSEN, a citizen of the United States, residing at Woodland, in the county of Yolo and State of California, have invented certain new and useful Improvements in Scrapers; and, I do declare the following to be a full, clear, and exact description of the invention, such as will enable others skilled in the art 10 to which it appertains to make and use the same.

This invention relates to scrapers, and it relates more particularly to an improved rotary scraper such as employed for grading 15 roads, etc.

One object of this invention is to provide for generally improving while minimizing the cost of devices of this character;

A further object is to provide for cushioning the shock consequent to the stopping of the rotary scraper element, and to utilize portions of the main frame for backing the cushioning means; and

A further object is to provide a device of 25 this character which is strong and rigid and yet comparatively light.

Other objects and advantages may become apparent to persons who read the following details of description in connection with the 30 accompanying drawings, in which:

Figure 1 is a top plan view of a scraper constructed in accordance with the present invention;

Fig. 2 is a side elevation of the device 35 shown in Fig. 1;

Fig. 3 is a vertical horizontal sectional view taken along the line 3—3 of Fig. 1;

Fig. 4 is a transverse vertical sectional view taken along the line 4—4 of Fig. 1;

Fig. 5 is a fragmental detail view illustrating stop-levers in a position at which the rotary scraper element is free from engagement therewith; and,

Fig. 6 is a perspective view showing the 45 relation of one of the stop-lugs to one of the stop-levers.

Referring to these drawings in detail, in which similar reference characters correspond with similar parts throughout the 50 several views, the main frame, which is indicated bodily by the numeral 7, consists of side beams 8, forwardly converging end beams 9, and cross beams 10, 11, 12 and 13. The beams 8 to 13 inclusive are preferably 55 formed of angle iron or steel, and the cross beams are each formed with apertured end

flanges which are secured to the side beams 8 by rivets 14 or by other appropriate means. The side beams 8 and the end beams 9 may be formed from a single length of 60 angle iron or from separate lengths and united at the front end, and these beams lie in the same common plane with one another and with the cross beams 10, 11, 12 and 13. It will be seen, therefore, that a very simple 65 and yet rigid and strong main frame is provided.

The main frame 7 is carried by wheels 15 and 16, the former being pivotally mounted on an arm 17 which is pivotally mounted on the frame 7 at 18; and the wheels 16 are connected to the frame 7 by means of an axle 19 which has bifurcated ends 20 turned at right angles to the middle portion of the axle, bearings 21 being provided on the frame for this axle. A sleeve or hub 22 is secured on the axle 19 and carries a hand-lever 23 and a foot-lever 24, and by moving either of the levers 23 or 24, the rear end of the frame 7 may be raised or lowered. 70 However, for convenience sake, the lever 23 is usually employed for raising or lowering the rear end of the frame while the foot-lever 24 is employed for holding the rear end of the frame temporarily in its raised 75 position. A spring 25 has one end connected to the lever 23 and has its other end connected to the rear end of the frame 7, and this spring continually tends to throw the lever 23 rearward and thereby tends to force 80 the rear end of the frame upward so as to regulate the depth to which a scraper element (hereinafter described) scrapes the earth's surface. The lever 23 is held in different adjusted positions by means of two 85 segments 26 having apertures 27 therein and a pin 28 seated alternatively in corresponding apertures.

Approximately at the central part of the frame 7 is provided bearings 29 in which 90 a shaft 30 is mounted. This shaft carries a pair of wheels 31, and between these wheels is mounted a scraper element 32 which has its ends secured to the wheels at 95 33 and is rotatable therewith.

Each of the scraper elements 32 comprises a plurality of wooden beams 34 in parallel and juxtaposed relation to one another and constituting the body of the scraper element; a pair of excavating 100 blades 35, the latter being set substantially 105 at opposing tangents to the wheels 31; and

a plurality of securing and bracing strips of metal 36 which securely unite the blades 35 with the wooden beams 34. By means of this peculiar construction, I provide a very strong, rigid, durable and thoroughly practical scraper element at the minimum cost. At points on the periphery of the wheels 31 I provide stop elements or lugs 37 which extend radially from the wheels

10 and coöperate with stop levers 38 for holding the wheels in the position for holding the blades 35 alternately in the operative position, that is, in the position for scooping up earth from the earth's surface. The 15 levers 38 are pivotally mounted at 39 on the lower side of the cross beam 11, and each of these levers is movable into and out of the path of rotation of the stop elements or lugs 37 on one of the wheels 31. 20 The outer end of each lever 38 extends under the adjacent side beam 8 and is normally spaced a slight distance below this side beam. Each of the levers 38 is preferably formed of a flat piece of springy 25 plate metal and is movable against the adjacent side beam 8 by the upward pressure of the adjacent lugs 37, and returns to its normal spaced relation when the said upward pressure is relieved.

30 Upon the cross beams 12 is mounted a pair of angle elements 40 which constitute a bearing for a lever 41 which extends upward therefrom. The lower end of this lever is pivotally connected at 42 to two links or connections 43, the latter being pivoted at 44 to the inner ends of the lever 38. A plate 45 is supported on beam elements 11, 12 and 13 and extends rearwardly therefrom so as to form an extension of the 40 main frame; to this extension the rear end of the spring 25 is secured, while on the plate 45 is supported a seat-spring 47 on which is supported a driver's seat 48. Bracing and supporting bars 46 are carried by 45 the beam elements 11, 12 and 13, and help to support the platform 45.

The operation of this scraper is as follows:

Assuming that the device is being drawn 50 along the earth's surface in the direction of the arrow in Fig. 2, the stop lever 38 being engaged with the stop element 37, the wheels 31 and scraper element 32 are prevented from rotating, and the earth's surface is scraped by the lower one of the blades 35 until the desired amount of earth has been accumulated by the scraper; whereupon the lever 41 is shifted in the manner for pushing the inner ends of stop levers 55 60 65 38 forward, thereby drawing the outer ends rearward out of engagement with the stop elements 37. After the wheels and scraper element have rotated through an angle of between 90 and 180 degrees, the lever 41 is again pushed forward, thereby interposing

the outer end portions of the levers 38 in the path of the rotating stops 37. When the stops 37 strike the levers 38, the latter yield slightly so as to cushion the scraper, and their movement is arrested by them 70 coming into contact with the lower side of the beams 8, which position arrests further movement of the scraper element with relation to the main frame.

It will be noted that the path of each 75 lug 37 is adjacent to one of the side beams 8 and also adjacent to the cross beam 11, and therefore these beams 8 and 11 supplement the relatively light and yielding levers 38 in holding the scraper element in 80 its operative position.

Although I have described this embodiment of my invention very specifically, it is not intended to limit my invention to these exact details of construction and arrangement of parts, but I am entitled to make minor changes within the scope of the foregoing description and following claims.

What I claim as my invention is:

1. In a scraper, a frame movable along the earth's surface and comprising side beams and a cross beam, the latter having its ends secured to said side beams; a scraper element having parallel earth-scraping edges and being rotatably supported by said side beams, its axis of rotation being between and parallel with said edges; stop elements extending radially from the ends of said scraper to points adjacent to the respective side beams and being rotatable with 100 said scraper element; and stop-levers each fulcrumed on said cross beam and movable into and out of the path of rotation of certain ones of said stop elements and being engaged with one of said side beams and thereby supplemented in detaining said scraper element against rotation.

2. In a scraper, a frame movable along the earth's surface and comprising side beams and a cross beam, the latter having its ends secured to said side beams; a scraper element having parallel earth-scraping edges and being rotatably supported by said side beams, its axis of rotation being between and parallel with said edges; stop elements extending radially from the ends of said scraper to points adjacent to the respective side beams and being rotatable with said scraper element and to said cross beam; and stop levers each pivotally secured to the lower side of said cross beam and having one end portion in position to move into and out of the path of rotation of certain ones of said stop elements and being engageable with the lower side of said cross beam and of the adjacent side beam and thus being supplemented in detaining said scraper element against rotation.

3. In a scraper, a frame movable along the earth's surface and comprising side beams 130

and a cross beam, the latter having its ends secured to said side beams; a scraper element having parallel earth-scraping edges and being rotatably supported by said side beams, 5 its axis of rotation being between and parallel with said edges; stop elements extending radially from the ends of said scraper to points adjacent to the respective side beams and being rotatable with said scraper ele- 10 ment; stop-levers each fulcrumed on said cross beam and movable into and out of the path of rotation of certain ones of said stop elements and being engageable with one of said side beams and thereby supplemented 15 in detaining said scraper element against rotation, a second cross beam, a controlling lever fulcrumed on the said second cross beam, and connections whereby both of said

stop levers can be simultaneously operated by said controlling lever. 20

4. A scraper element comprising a pair of wheels each provided with a pair of stop elements projecting radially therefrom, a wooden plate disposed between said wheels and having its ends secured thereto, a pair 25 of blades secured on two opposite edges of said plate, and a plurality of strips connecting said blades with one another and reinforcing said wooden plate.

In testimony whereof I have hereunto set 30 my hand in the presence of two subscribing witnesses.

HENRY B. GERMESHAUSEN.
